UNITED STATES PATENT OFFICE

EDWARD Z. LEWIS, OF CHICAGO, ILLINOIS, ASSIGNOR TO L C SMITH & CORONA TYPE-WRITERS INC., OF NEW YORK, N. Y., A CORPORATION OF NEW YORK

METHOD AND MEANS FOR TYPEWRITING LONG STRIPS OF PRINTED FORMS

Application filed August 25, 1928. Serial No. 302,110.

My invention relates to improvements in methods and means for feeding a plurality of long strips of printed forms into a typewriter, said strips being superimposed on each other and interleaved with carbon sheets, whereby the filling in of the successive forms with typewritten matter, and the production of the requisite number of carbon copies may proceed practically continuously. 10 The invention is an improvement over the structure of my co-pending application Serial No. 21,502, filed April 8, 1925, now Patent No. 1,699,794, dated January 22, 1929.

The general object of the present invention 15 is to provide a method and means for effecting this result.

Contributory objects are the following:

To provide means for folding over the first set of forms against the second set of forms, 20 drawing the loops of paper thus formed around the platen by rotating the same backward by hand, typing the forms in the usual manner, pulling them forwardly over the carbons which are held in place against forward movement and cutting off the finished forms. 25

To provide means for clamping the paper against the platen as the latter is rotated reversely by hand whereby the loops are formed automatically when the paper is pulled down 30 past the feed rolls.

To provide a platen having a recess in which the loops are received.

To provide overhanging supporting rods to which the carbon sheets may be readily attached. 35

To provide these improvements in the form of an attachment which may readily be applied to any standard typewriter by merely substituting a special platen for the one 40 in use.

To provide a knife for cutting off the finished forms.

Other objects and advantages will be apparent from a consideration of the embodiments of the invention illustrated in the drawings, in which continuous typing is accomplished merely by turning the knobs on the platen shaft to rotate the platen first in the reverse direction from that in which it 45 rotates step by step during the typing oper-

ation, then after typing the forms pulling out the paper and tearing off the forms without having to release the feed rollers, draw back the carbons or carry out any of the other operations heretofore required, or exercise 55 any special care in such operations as are performed.

Fig. 1 is a side elevation of a typewriter having my improvements incorporated therewith; 60

Fig. 2 is an enlarged end elevation of the platen; 65

Fig. 3 is an end elevation of the carriage showing the paper and carbons before beginning the operation;

Fig. 4 is a front elevation of the platen;

Fig. 5 is an enlarged elevation of one of the duplex bars for supporting two of the carbon sheets;

Fig. 6 is an elevation of a modified and preferred form of duplex bar support; 70

Fig. 7 is an end view thereof; and

Fig. 8 is a small diagrammatic view illustrating the operation of the device.

Referring to the drawings, 1 represents 75 an ordinary typewriter which may be of any approved design, the one selected for illustration being well known. In addition to the usual parts it has a knife 2 in front of the platen 3. This platen is mounted on the 80 usual shaft 4 having bearings 5 and the usual ratchet 6, the latter, however, being spaced from the end of the platen to provide a clearance between the two. A clamp bar 7 is pivotally supported on the platen having its ends 85 8 bent downwardly and then inwardly to form pivotal supports 9, received in end openings in said platen.

A plurality of metal frames or bars are provided for supporting sheets of carbon paper. 90 They may be made in various forms and operated different ways. One of these carbon holders, see Fig. 5, consists of a small rod 10 passing through an opening in the platen and having detachable ends 11 extending upwardly and then inwardly to form bars 12 and 13 spaced from each other and supported by one end only, whereby they overhang the platen. Each of these bars is 95 adapted to support a sheet of carbon paper, 100

as hereinafter explained. A second similar frame comprises the rod 14 having bent ends 15 and overhanging bars 16 and 17, each of the latter adapted to support a sheet of carbon paper.

5 The clamping frame and the two carbon frames are each provided with pins 18, 19 and 20 (Figs. 2 and 3) which limit their movement in one direction. They may be swung in the other direction, however, into the recess 10 21 in the platen as shown in Fig. 2.

In using the machine a plurality of long strips of printed forms are pulled forwardly, face downwardly, along the top of the platen. Horizontal bars 12, 13, 16 and 17 to each of 15 which one end of a sheet of carbon paper is secured, are placed between said strips of printed forms. The ends of these supporting rods extend beyond the lateral edges of the strips of paper and are then attached to the rod 10. In the form shown in the drawings, Fig. 3, provision is made for five such printed forms 22, said printed forms being stored at the rear, in the usual manner. Provision is 20 made in this instance for four sheets of carbon paper 23, the rear end of each of which is looped around one of the bars 12, 13, 16 or 17, the carbon paper being pasted to itself to form an open loop, whereby these loops 25 may readily be slipped over said rods, half of them from one end and the other half from the other end thereof, as will be understood from an examination of Figs. 4 and 5. The sheets of carbon paper are a little shorter 30 than the height of the superimposed forms whereby the latter initially extend beyond the carbons as shown in Fig. 3 to facilitate grasping the same by hand.

The preferred form of carbon support is 40 shown in Figs. 6, 7 in which the transverse rod 24 has its ends bent upwardly, one of them being bent outwardly, and the other being bent inwardly as at 25 and 26, these bent portions constituting guides to receive the 45 detachable rods 27 over which the carbon paper is slipped. Many platens are hollow thus permitting the bar 24 with its upwardly bent ends to pass through the same before the end plates are secured thereto. The rods 27 50 are arranged one in front of the other.

The printed forms are guided in their movement toward the platen by a member 28 secured to the carriage and having its ends bent upwardly to form vertical guides. Also 55 the clamp bar 7 is struck upwardly as shown at 29, leaving a pair of shoulders which guide the paper over the platen.

In using the typewriter, the operator turns the platen by hand in a direction the reverse 60 of the usual operation, whereupon the clamp 7 and the carbon supporting frames are moved toward the platen. In the particular mechanism shown herein the said parts tend to swing to the rear along the arc of a circle 65 as the forward movement of the paper is ob-

structed more or less by the upper end of the two spring pressed feed roll supports 30, which carry the feed rolls 31 and the knife 2, and thus the paper is automatically clamped to the platen at a predetermined distance 70 from the end of said sheets, i. e. a distance approximately equal to the length of a printed form. Although the clamping member moves inwardly along the arc of a circle, it is evident that it may be caused to move inwardly in any one of a number of different ways. The latter cause the superimposed layers to fold over themselves in the form of loops around the clamp bar as suggested in Fig. 8, and the folded parts are then drawn down the front of the platen and around the same by the simple operation of rotating said platen by hand in the reverse of the usual direction to approximately the position shown in Fig. 2. Thus there is presented to 80 the type 33 and the ribbon 34 a group of sheets having twice the thickness of the number of printed forms desired with interleaved carbons between the outer half of the sheets of said group. The inner half merely serve 85 as a backing.

As the typewriter is operated in the usual way, beginning at the top line to be filled in, the platen is rotated in the usual direction, i. e., forwardly, and the forms are gradually 95 fed out of the machine until the bottom line is reached in which position the clamping bar and associated carbon holding bars will have been rotated from the position shown in Fig. 2 almost to the printing line, after 100 which the operator turns the platen by hand a little further in the same forward direction to feed the printed forms completely out of the machine. Thereupon the operator seizes the forward ends of said forms, which as 105 stated, project perhaps half an inch beyond the forward end of the carbon sheets, about as shown in Figs. 1 and 3, and by pulling said forms forwardly, the carbon sheets are left behind, being held in place by the transverse 110 bars to which they are attached, so that said printed forms slide over the carbons leaving a second set of forms in proper typing position with reference to the carbons. The platen is then rotated in the reverse direction, in the manner previously described, leaving the completed forms projecting from the top of the machine with no carbons between them whereupon they are seized and torn off against the knife 2, which is located 115 just in front of the platen. The typing operation then proceeds and the operations are repeated. Such rotation is made possible by virtue of the recess 21 into which the various cross bars swing, so that said cross bars and 120 the paper looped thereover do not protrude beyond the surface of the platen to an objectionable extent. In other words, where a small number of carbon copies are to be made, one or two, it may be possible in some 125 130

cases to use an ordinary platen without a recess cut therein, as the projection caused by the loops of paper will ride under the feed rollers 31 which spring back sufficiently for the purpose. Said cross bars are arranged 5 to fall back in said recess independently of each other, and are arranged to lie side by side rather than one over the other so as to fit into the available space very compactly.

10 The improvements may be applied to an ordinary typewriter merely by supplying a special platen, which may be placed in the bearings from which the regular platen has been removed to permit the use of my improved platen. Additional feed rolls are unnecessary 15 as the paper loops are clamped against the platen by the pivoted clamp, which holds them in place without additional feed rollers. It will be understood that the printed forms in practice are very long, enough to 20 supply several thousand individual printed forms and are conveniently stored to the rear of the typewriter, whereby after said forms are once threaded through the machine with 25 the carbon sheets between them, it is unnecessary to interrupt the typing operation, and the work may proceed as a continuous operation.

Another type of printed form which may 30 be used is one having its alternate lateral edges joined, in a well known manner.

Although as shown in Fig. 2, the length of each printed form is less than the circumference of the platen, it is possible to use printed 35 forms having a greater length, necessitating rotation of the platen more than a complete turn, particularly when the vertical height of the typing area is no greater than the circumference of the platen.

40 As will be seen in Fig. 2, the arrangement of the clamping bar and the carbon holding bars is such that said bars fold into the recess in the platen in such a way that the paper does not project too far beyond the normal circumference of said platen. The carbon holding bars shown in this figure are arranged in pairs one over the other. In the preferred arrangement shown in Figs. 6 and 7, the carbon holding bars are not only arranged one over the 45 other, but they are displaced circumferentially, that is, one is arranged in advance of the other, the rear one being the higher of the two and the end view of the support for the bars being V shaped as shown in Fig. 7. When 50 this V shaped frame is folded rearwardly, the two bars lie nearer the surface of the groove in the platen. In other words, a smoother arrangement is presented when all the bars are swung back into the groove.

55 Instead of having a series of individual bars with end portions extending at right angles thereto, a single structure may be provided at each end of the platen carrying not only the clamping bar but all of the carbon holding bars so that said bars maintain a

fixed relation as they swing up or down.

Although the devices shown are particularly useful in making a large number of carbon copies of typewritten matter, it is evident that the principle of operation is applicable 70 to a single sheet of paper and a single carbon sheet, in which case only the clamp bar is necessary, the carbon sheet being secured to the clamp bar and thus arranged to make the necessary carbon impression when the single 75 sheet of paper is folded back on itself. The carbon copy is thus made immediately to the rear of the area on which the original impression is made and on the opposite side of the paper, in which case the strip of paper 80 is drawn forwardly far enough to withdraw both the original and the carbon, in other words, twice as far as in the cases previously described.

By using the attachment described, it is 85 also possible to obtain a tabulation of the totals of the individual printed forms, where such is desired, merely by securing an additional narrow sheet of carbon paper to the clamping bar and passing an additional strip 90 of paper under said clamping bar and over the upper printed form. After each operation this strip of paper, which may be a wide sheet or merely a narrow strip at the right hand side of the machine, is pulled forward 95 a short distance, for example a half inch or less, enough to receive the successive totals thereupon, which appear in the reverse order, i. e. the totals read from the bottom up. If it is preferred to print the totals in consecutive 100 order from the top down, an additional carbon holding bar may be mounted on the platen to support a sheet of carbon paper between the top printed form and the tabulating sheet which passes under the clamping 105 bar.

The terms "top", "bottom", "front", "rear", "horizontal", and similar terms used herein as descriptive of the particular embodiment of the invention shown are to be understood 110 as used for convenience in a relative sense and not in a limiting sense. In general, various changes may be made in the form and location of parts and in the general design of the machine without departing from the spirit 115 of the invention as expressed in the appended claims.

What I claim is:

1. The combination with a typewriter, of 120 a platen having means for clamping a plurality of sheets of paper against the same, at a predetermined distance from the ends of said sheets, means for securing a sheet of carbon paper adjacent said platen, whereby when said platen is rotated in the reverse direction from the normal one used during typing, said sheets of paper are folded over and looped around said carbon paper and carried down around said platen and to the rear to typing position. 130

2. The combination with a typewriter platen having superimposed strips of paper extending from the rear substantially horizontally across the top of said platen, with 5 sheets of carbon paper between said strips, of means for pressing said paper against the upper part of said platen and means adjacent the front of said platen located to be engaged by the forwardly projecting part of 10 said paper when said platen is turned backward.

3. The combination with a typewriter platen having superimposed strips of paper extending substantially horizontally across 15 the top of the same, with sheets of carbon paper between said strips, of means for pressing said paper against the upper part of said platen, means adjacent the front of said platen located to be engaged by the forwardly 20 projecting part of said paper when said platen is turned backward, and a knife located in front of said platen.

4. The combination with a typewriter platen having superimposed strips of printed 25 forms extending substantially horizontally across the top of the same with sheets of carbon paper corresponding in size to said printed forms located between said strips, of a transverse bar movably mounted on said 30 platen for pressing said paper against the upper part of said platen and feed rollers yieldingly pressed against the front of said platen to be engaged by the forward group of printed forms when said platen is turned 35 backward, whereby said forward group is folded over against the group of forms immediately to the rear thereof.

5. The combination with a typewriter platen having strips of superimposed printed 40 forms extending substantially horizontally across the top of the same with sheets of carbon paper between said strips and a transverse bar movably mounted on said platen for pressing said paper against the upper 45 part thereon, feed rollers in front of said platen to be engaged by the forward part of said paper strips and cause said forward part to be folded on itself and additional transverse bars on said platen to which the 50 rear ends of said carbon sheets are attached.

6. The combination with a typewriter having a platen with a plurality of transverse bars secured thereto and substantially parallel to the axis of rotation of said platen, and 55 a plurality of carbon sheets having their rear edges only secured to said bars, the latter being arranged normally at different elevations.

7. The combination with a typewriter having a platen with a plurality of transverse bars each secured thereto at one end and overhanging said platen substantially parallel thereto and a plurality of carbon sheets each having a loop at its rear end slipped over one 65 of said bars.

8. The combination with a typewriter having a platen provided with a longitudinal opening and with a plurality of carbon supporting frames mounted thereon, each frame comprising a transverse member passing through said longitudinal opening in said platen and having its ends bent upwardly and then toward each other to provide two overhanging bars each supported at opposite ends. 70

9. A typewriter platen having a plurality of transverse bars movably secured thereto at different distances from the periphery thereof, the outmost bar serving as a clamping bar under which a sheet of paper may pass and each of the other bars having a sheet of carbon paper secured thereto, whereby additional strips of paper may be passed between said bars to receive a typing impression. 75

10. A typewriter platen having a groove therein parallel to its axis of rotation, two or more parallel bars on said platen also parallel to said axis, and means for swinging said bars side by side into said groove when said platen is rotated backwardly, said bars swinging away from said platen at graduated distances therefrom when said platen is turned to bring said bars on top of the same. 80

11. A typewriter platen provided with a series of parallel carbon paper holding bars mounted thereon at graduated distances and parallel to the axis thereof, means for automatically swinging said bars side by side against the surface of the platen when said platen is rotated backwardly, and means for holding said bars at graduated distances from the surface of said platen when it is rotated forwardly. 85

12. A typewriter platen having a series of parallel carbon paper holding bars mounted thereon at graduated distances and parallel to the axis thereof, means for automatically swinging said bars side by side against the surface of the platen when said platen is rotated backwardly, means for holding said bars at graduated distances from the surface of the platen when it is rotated forwardly, and means for guiding continuous strips of superimposed printed forms across the top of the platen and between said carbon holding bars. 90

13. A typewriter platen having a series of parallel carbon paper holding bars mounted thereon at graduated distances and parallel to the axis thereof, means for automatically moving said bars below the surface of the platen in a compact arrangement, when said platen is rotated backwardly, means for holding said bars at graduated distances from the surface of the platen when it is rotated forwardly, means for guiding continuous strips of superimposed printed forms across the top of the platen and between said carbon holding bars, and means in front of said platen to fold the forwardly projecting set of forms around 110 120 125 130

the forward bar and back to back against the next succeeding set of forms.

14. In combination with a typewriter having a platen with end plates, of a series of 5 parallel bars eccentrically pivoted on said end plates and adapted to swing against the surface of the platen when the latter is rotated reversely and arranged when in normal position on top of said platen at graduated distances therefrom to provide slots through which continuous strips of printed forms are drawn forwardly tangent to the top periphery of said platen and means for guiding said forms into typing position.

15. 15. A typewriter having a platen with a feed roller in front of the same above the typing area, a bar movable toward and away from said platen and around which a strip of paper is looped and thereby caused to rotate with said platen down past said feed roller, and a sheet of carbon paper attached, face up, at one edge to said bar.

16. In combination, a platen, a bar parallel thereto and mounted to move toward and 25 away from the periphery of said platen, said bar having shoulders thereon between which the paper may be guided, and a second pair of paper guiding members mounted to the rear of said platen.

30 17. In combination, a platen having a large opening therethrough, a bar passing through the same and having upwardly bent ends and carbon paper holding arms removably secured to said ends.

35 18. In combination, a hollow platen, a carbon holding frame comprising a transverse bar passing through the hollow platen and having right angled extensions at its ends, one of which is longer than the other and 40 arranged in a different radial plane from said other, and detachable carbon holding bars secured to the ends of said extensions whereby they are mounted at different distances from the center of the platen and 45 placed circumferentially.

19. In combination, a hollow platen having a groove therein, a carbon supporting frame comprising members pivoted to said platen and carbon holding bars secured one to each 50 of said members, one of said bars being arranged higher than the other and to the rear thereof whereby said bars may be swung into said groove substantially into contact with the wall thereof.

55 20. The combination with a typewriting machine, a platen; means for clamping a plurality of superposed sheets of paper against the platen a suitable distance inwardly from the ends of said sheets; means for securing a 60 sheet of carbon paper adjacent said platen and between said paper sheets; and means whereby when said platen is rotated in the reverse direction from the normal one used in line spacing, said sheets of paper are folded over into a loop with said carbon paper;

said loop being carried down in front of the platen and around to the rear thereof to bring the desired point on the folded form to the proper point on the platen for typing.

21. The combination with a typewriting machine, a platen; means for clamping a sheet of paper to the platen at a suitable distance inwardly from the forward end of said paper; and means cooperating with the platen and adjacent thereto and adapted to be engaged by the forwardly projecting free portion of the paper when the platen is rotated opposite to the direction in which it is rotated for line spacing, whereby the free portion of the paper forward of the platen will be folded up and back on the remaining portion of the paper and the folded edge will be carried down in front of the platen to place the desired point on the folded form at the typing point. 70

22. The combination with a typewriting machine, of a platen; means for clamping a sheet of paper to the platen at a suitable distance inwardly from the forward end of said paper; and means cooperating with the 80 platen and adjacent thereto and adapted to be engaged by the forwardly projecting free portion of the paper when the platen is rotated opposite to the direction in which it is rotated for line spacing, whereby the free portion of the paper forward of the platen will be folded up and back on the remaining portion of the paper and the folded edge will be carried down in front of the platen to place the desired point on the folded form at the typing point. 85

100

105

110

115

120

125

130

23. The combination with a typewriting machine of a platen; a clamping means parallel with the axis of the platen and extending across the machine above the platen when the platen is in normal non-typing position, whereby a plurality of superimposed strips of paper may be extended from the rear of the machine substantially horizontally across the platen between the clamping means and the platen with sheets of carbon paper interleaved between said paper strips; means for causing said clamping means to press the paper strips against the platen; and means adjacent the front of said platen and adapted to be engaged by the forwardly projecting parts of said paper strips when said platen is turned backward in a direction opposite the direction of rotation during line spacing, whereby said forward projecting parts of the paper strips will be carried upwardly backwardly to form a loop at the clamping means and said looped portion of the strips will be carried forward and down opposite

the typing point to bring the desired point on the folded form into typing position.

24. The combination with a typewriting machine, of a platen; a clamping means parallel with the axis of the platen and extending across the machine above the platen when the platen is in normal non-typing position whereby a plurality of superimposed strips of paper may be extended from the rear of the machine substantially horizontally across the platen between the clamping means and the platen with sheets of carbon paper interleaved between said paper strips; means of causing said clamping means to press the paper strips against the platen; means adjacent the front of said platen and rotated to be engaged by the forwardly projecting parts of said paper strips when said platen is turned backward in a direction opposite the direction of rotation during line spacing whereby said forward projecting parts of the paper strips will be carried upwardly backwardly to form a loop at the clamping means and said looped portion of the strips will be carried forward and down opposite the typing point to bring the desired point on the folded form into typing position; and a knife located in front of said platen whereby the line-spacing operation of the platen will return the forms to their original unfolded positions to permit the typed form to be torn off by the knife.

25. A combination with a typewriting machine, of a platen; a transverse clamping bar movably mounted on said platen, said bar being parallel with the axis of the platen and above the platen in the normal non-typing position of the platen whereby superimposed strips of printed forms may be extended substantially horizontally across the top of the platen below said clamping bar with the end-most group of forms substantially forward of the clamping bar, and sheets of carbon paper corresponding in size to said printed forms may be located between said strips; means whereby said transverse clamping bar will yieldingly press said paper strips against the platen; and feed rollers yieldingly pressed against the front of said platen and adapted to be engaged by the forwardly extending group of printed forms when said platen is turned backward in a direction opposite its line spacing direction and whereby said forwardly projecting group of forms will be folded up and back against the next adjacent group of forms and the loop thus formed will be carried down beyond the feed rollers at the front of the platen to bring the desired point on the folded-back forms in position for typing.

26. A combination with a typewriting machine, of a platen; a transverse clamping bar movably mounted on said platen, said bar being parallel with the axis of the platen and above the platen in the normal non-typing

position of the platen whereby superimposed strips of printed forms may be extended substantially horizontally across the top of the platen below said clamping bar with the end-most group of forms substantially forward of the clamping bar, and sheets of carbon paper corresponding in size to said printed forms may be located between said strips; means whereby said transverse clamping bar will yieldingly press said paper strips against the platen; feed rollers yieldingly pressed against the front of said platen and adapted to be engaged by the forwardly extending group of printed forms when said platen is turned backward in a direction opposite its line spacing direction and whereby said forwardly projecting group of forms will be folded up and back against the next adjacent group of forms and the loop thus formed will be carried down beyond the feed rollers at the front of the platen to bring the desired point on the folded-back forms in position for typing; and transverse carbon sheet carrying bars mounted on said platen substantially parallel with the clamping bar.

27. The combination with a typewriting machine, of a platen; a plurality of transverse bars secured thereto at different distances from the periphery thereof, the outermost bar serving as a clamping bar and being movable toward the platen, the other of said bars serving as carbon sheet carrying bars, whereby in the normal non-typing position of the platen a strip of paper may be passed under the said clamping bar and over the other bars and other strips of paper may be inter-leaved with the carbon sheets carried by said bars; means whereby the rotation of the platen in a direction opposite to its line-spacing direction will cause the clamping bar to clamp the sheets to the platen; and means whereby said rotation of the platen will cause the inter-leaved paper strips and carbon sheets to fold upwardly and backwardly and the loop thus formed around the clamping bar will pass forwardly and down in front of the platen to bring the desired point on the folded-back strip to typing position.

28. The combination with a typewriting machine, of a platen; a plurality of transverse bars secured thereto at different distances from the axis of the platen, the outermost bar serving as a clamping bar and being movable toward the platen, the other of said bars serving as carbon sheet carrying bars whereby in the normal non-typing position of the platen a strip of paper may be passed under the said clamping bar and over the other bars and other strips of paper may be inter-leaved with the carbon sheets carried by said other bars; and means whereby the rotation of the platen in a direction opposite to its line spacing direction will cause the inter-leaved paper strips and carbon sheets to fold upwardly and backwardly over the

clamping bar, and the loop thus formed around the clamping bar will pass forwardly and down in front of the platen to bring the desired point on the folded back strip to typing position and whereby the line-spacing operation of the platen will feed the folded strips out of the machine and back to their original unfolded forward-stripping position.

29. The combination with a typewriting machine, of a platen; a plurality of transverse bars secured thereto at different distances from the axis of the platen, the outermost bar serving as a clamping bar and being movable toward the platen, the other of said bars serving as carbon sheet carrying bars whereby in the normal non-typing position of the platen a strip of paper may be passed under the said clamping bar and over the other bars and other strips of paper may be inter-leaved with the carbon sheets carried by said other bars; means whereby the rotation of the platen in a direction opposite to its line spacing direction will cause the inter-leaved paper strips and carbon sheets to fold upwardly and backwardly over the clamping bar, and the loop thus formed around the clamping bar will pass forwardly and down in front of the platen to bring the desired point on the folded back strip to typing position and whereby the line-spacing operation of the platen will feed the folded strips out of the machine and back to their original unfolded forward-stripping position; and a tear-off knife in front of the platen in position to be engaged by the forwardly stripped typed portions of the paper strips when the next adjacent untyped portions of the paper strips are wound on the platen to typing position.
30. The method of typing a plurality of long webs, each web consisting of a plurality of forms to be typed, which consists in inter-leaving said web forms with carbon sheets; positioning the inter-leaved webs and carbon sheets across the top of the platen and fore and aft of the machine with the printed faces of the webs down and with the first form toward the operator and forward of the platen; clamping the inter-leaved webs to the platen to hold them against relative shifting movement; rotating the platen to carry the clamped portion of the webs forward and down around the platen in a direction reverse to the line-spacing direction of the platen to thereby fold the forward or end forms upward and back upon the next adjacent forms, the loop in the inter-leaved webs thus formed being carried down in front of the platen and around to the rear thereof to bring the desired point on the outermost form into typing position, the folding of the inter-leaved forms bringing the printed faces of the forms to the front of the platen for the typing operation.
31. The combination with a typewriting machine of a platen; a retaining bar parallel

with the axis of the platen and extending across the machine at the top of the platen when the platen is in normal non-typing position with a space between said bar and the body of the platen whereby a plurality of superimposed strips of paper may be extended from the rear of the machine substantially horizontally across the platen between the retaining bar and the body of platen with sheets of carbon paper inter-leaved between said paper strips; and means adjacent the front of said platen and adapted to be engaged by the forwardly projecting parts of said paper strips when said platen is turned backward in a direction opposite the direction of rotation during line spacing, whereby said forward projecting parts of the paper strips will be carried upwardly and backwardly to form a loop over the retaining bar and said looped portions of the strips will be carried forward and down opposite the typing point to bring the desired point on the folded forms into typing position.

In testimony whereof, I have subscribed my name.

EDWARD Z. LEWIS.
